US0D1075844S

(12) **United States Design Patent** (10) **Patent No.:** **US D1,075,844 S**
(45) **Date of Patent:** **** May 20, 2025**

(54) **TIMING COVER**

(71) Applicant: **Holley Performance Products, Inc.**,
Bowling Green, KY (US)

(72) Inventors: **Coy Hudnall**, Bowling Green, KY
(US); **Kevin Tracy**, Port Charlotte, FL
(US)

(73) Assignee: **Holley Performance Products, Inc.**,
Bowling Green, KY (US)

(**) Term: **15 Years**

(21) Appl. No.: **29/860,950**

(22) Filed: **Nov. 23, 2022**

(51) **LOC (15) Cl.** **15-01**

(52) **U.S. Cl.** **D15/5**
USPC **D15/5**

(58) **Field of Classification Search**

USPC D15/1-6, 149
CPC . F16H 15/28; F02F 7/0073; F02F 2007/0075;
F02F 2007/0078

(57) **CLAIM**

The ornamental design for a timing cover as shown and described.

DESCRIPTION

FIG. 1 is a first perspective view of a design of a timing cover;

FIG. 2 is a second perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1; and,

FIG. 8 is a bottom view of the design of FIG. 1.

In the drawings, the broken lines depict portions of the timing cover that form no part of the claimed design.

1 Claim, 8 Drawing Sheets
